US00D758230S

(12) **United States Design Patent**
Hojmose

(10) **Patent No.:** **US D758,230 S**
(45) **Date of Patent:** **** Jun. 7, 2016**

(54) **SMOKE ALARM**

(71) Applicant: **Cavius ApS**, Silkeborg (DK)

(72) Inventor: **Glenn Hojmose**, Silkeborg (DK)

(73) Assignee: **Cavius APS**, Silkeborg (DK)

(**) Term: **14 Years**

(21) Appl. No.: **29/484,043**

(22) Filed: **Mar. 5, 2014**

(30) **Foreign Application Priority Data**

Sep. 5, 2013 (EM) 002303180

(51) **LOC (10) Cl.** **10-06**

(52) **U.S. Cl.**

USPC **D10/106.5**

(58) **Field of Classification Search**

(57) **CLAIM**

The ornamental design for a smoke alarm, as shown and described.

DESCRIPTION

FIG. 1 is a front elevation view of the smoke alarm;

FIG. 2 is a front perspective view of the invention shown in FIG. 1;

FIG. 3 is a top perspective view of the invention shown in FIG. 1;

FIG. 4 is a top plan view of the invention shown in FIG. 1; and,

FIG. 5 is a bottom plan view of the invention shown in FIG. 1. The broken lines (where present) in FIG. 5 illustrate portions of the smoke alarm that form no part of the claimed design.

1 Claim, 5 Drawing Sheets
